PROCESS OF MANUFACTURING INSIDE
FROSTED BULBSTomisaburo Naruse, Minamishinagawa,
Shinagawa-ku, Tokyo, JapanApplication March 21, 1933, Serial No. 661,960
In Japan November 26, 1932

3 Claims. (Cl. 41—42)

The invention relates to the type of process of manufacturing an inside frosted bulb, in which an etching liquid is poured in the interior of the bulb by means of a liquid supply pipe, and then the liquid supply thus charged is sucked out by a pipe.

According to the feature of the invention, the corrosive or etching liquid, during the time it is injected into the bulb, is subjected to an agitating motion at the outlet end of the pipe near the tip of the bulb, either by putting the liquid flow in a whirling movement, or by dividing the liquid flow into a plurality of streams, or by dispersing the liquid flow by means of an obstacle, arranged for the purpose between the outlet end of the pipe and the inside tip of the bulb, and then the corrosive or etching liquid thus charged into the bulb is sucked out therefrom, by means of a pipe lowered down close to the inside tip of the bulb, and immediately after such single etching operation, washing water is poured into the bulb to cleanse the latter.

In the known method for frosting the inside of a bulb, the corrosive liquid is caused merely to flow out of a supply pipe having the form of a cylinder, and therefore, the frosting result obtained at the part of the bulb, where the flow or flux of the liquid concentrates, is much different from those obtained at other parts of the bulb, and is often accompanied by specks or spots.

The invention has for its purpose to obviate such drawbacks, and also to obtain a uniform frosting of the inside of the bulb.

Other features and advantages of the invention are described below with reference to the attached drawing, which illustrate by way of examples, embodiments of apparatus for carrying out the invention, and in which:

Fig. 1 is a general view in a cross section of one embodiment; Fig. 2 is a cross section of the liquid supply pipe with the device mounted in the outlet end thereof, said pipe and device are in a position where the liquid is to be poured;

Fig. 3 is a similar view to Fig. 2, but in this case, the pipe and the device are arranged for the liquid to be sucked out;

Figs. 4, 5, 6 and 7 show four devices adapted to be mounted in the outlet end of the supply pipe, and adapted for giving an agitating motion to the corrosive or etching liquid; Fig. 8 shows in a cross section a modified embodiment; and Fig. 9 shows a device adapted to be mounted in the pipe extension of Fig. 8.

Referring to Fig. 1, the reference 1 shows a

bulb, which is placed on a stand with its mouth directed upwards, and the etching liquid 5 is injected into the interior of the bulb under pressure by means of one or more supply pipes 2, and the liquid thus charged is sucked out by the pipe, and in this way an inside frosted bulb is obtained. In the known methods, however, a supply pipe having the form of a cylinder is used, and the etching liquid is caused merely to flow out of the pipe into the interior of the bulb, with the result that the liquid flow is obliged to concentrate at a local part, and consequently, the frosting result obtained at the part of the bulb, where the flow concentrates, is quite different from that obtained at other parts of the bulb, and is also accompanied by specks or spots.

According to the invention, the etching liquid, during the time it is injected into the interior of the bulb, is subjected to an agitating motion, whereby the result is obtained, that the difference between the frosting degrees at the two parts is reduced to minimum, and at the same time specks or spots never appear. Moreover, according to the invention a uniform frosting is obtained due to the fact that the etching liquid, after having been subjected to an agitating motion, can be evenly distributed within and over the inside of the bulb. Further, if such an etching liquid contains powdered materials, such as cornflour, admixed therein, the frosting can be considerably improved.

According to the invention, a partial frosting can also be obtained easily, as the etching liquid subjected to an agitating motion at the outlet end of the supply pipe near the tip of the bulb is prevented from reaching the uppermost part of the bulb, and a distinct boundary line is marked between the frosted part and the transparent part.

The manner of carrying out the invention is now explained with reference to the drawing. The bulb 1 is placed on a stand with its mouth directed upwards, and the supply pipe 2 is inserted in the interior of the bulb, and an etching liquid 5, contained in a compression vessel 3 connected with the pipe 2, is injected into the interior of the bulb. By means of a piston 4, the liquid is alternately made to descend and ascend therein by compression and suction respectively. According to the invention, a device adapted for giving an agitating motion to the flow of the etching liquid is mounted in the outlet end of the supply pipe 2. Such device is illustrated, by way of examples, in the different figures by the nozzles b, c, d, e, f and g. These devices are mounted

within the cylindrical hollow body 6 and its extension 7 forming the outlet end of the pipe 2, and are adapted to give an agitating motion to the flow of the etching liquid flowing out of the 5 pipe 2 near the tip of the bulb, either by putting the liquid flow in a whirling movement, or by dividing the flow into a plurality of streams. The devices shown in Figs. 5 and 7 as nozzles *d* and *g* are adapted to cause a whirling motion, and those 10 shown in Figs. 4, 2 and 6 by nozzles *c*, *e*, and *f* are adapted for dividing the liquid into a plurality of radial streams. As the liquid is thus put in an 15 agitating movement, its flowing direction is, of course, deviated, and the liquid is evenly distributed over the inside of the bulb. The spherical and semispherical members shown in Figs. 2, 4 and Fig. 6 are two examples of an obstacle or baffle adapted for dispersing the liquid.

The etching liquid which has thus been changed 20 into the interior of the bulb is subsequently sucked out by the supply pipe 2. For this purpose, said pipe is lowered down to come close to the inside bottom of the bulb, and the piston 4 is put in operation, whereby the liquid is sucked out upwardly 25 from near the tip of the bulb (see Fig. 3 and Fig. 8). The etching or frosting operation is thus completed in a single operation. After this single etching operation, washing water is poured into the bulb to cleanse the inside thereof, and the bulb 30 is finally dried ready for use.

The inside surface thus frosted is of a beautiful milky colour, and the tone of the colour, in its uniformity, is accordingly far superior in comparison with that obtained by the known methods.

35 I claim:

1. Process for frosting the interior of a bulb, in which an etching liquid being mixed with powdered materials of the cornflour type is injected into the bulb through its upwardly directed 40 neck and then sucked out therefrom in opposite direction; consisting in subjecting the said liquid to agitating motion while it is injected under pressure into the bulb by a pipe, such agitating motion, by the aid of an agitating means attached 45 to the pipe end, taking place adjacent the tip of

said bulb, making the distance between the tip of the bulb and the opening of the pipe shorter, subsequently sucking out such liquid upwardly through the pipe from near the tip of the bulb and pouring water into the bulb immediately after the completion of the etching operation to clean the bulb. 5

2. Process for frosting the interior of a bulb, in which an etching liquid mixed with powdered materials of the cornflour type is injected into the 10 bulb through its upwardly directed neck and then sucked out therefrom in opposite direction: consisting in subjecting the said liquid to agitating motion, by dividing the liquid flow into a plurality of streams near the tip of the bulb, while it is injected by a pipe, under pressure, into the bulb, such agitating motion, by the aid of an agitating means attached to the pipe end, taking place adjacent the tip of the bulb, making the distance 15 between the tip of the bulb and the opening of the pipe shorter, subsequently sucking out such liquid upwardly through the pipe from near the tip of the bulb and pouring water into the bulb immediately after the completion of the etching 20 operation to clean the bulb. 25

3. Process for frosting the interior surface of a bulb, in which an etching liquid mixed with powdered materials of the cornflour type is injected into the bulb through its upwardly directed 30 neck and then sucked out therefrom in opposite direction: consisting in subjecting the said liquid to agitating motion, by whirling the liquid near the tip of the bulb, while it is injected by a pipe, under pressure, into the bulb: such agitating motion, by the aid of an agitating means attached 35 to the pipe end, taking place adjacent the tip of the bulb, making the distance between the tip of the bulb and the opening of the pipe shorter, subsequently sucking out such liquids upwardly 40 through the pipe from near the tip of the bulb and pouring water into the bulb immediately after the completion of the etching operation to clean the bulb. 45
